(57) **CLAIM**

The ornamental design for an atmospheric water generator unit, as shown and described.

DESCRIPTION

FIG. 1 illustrates a front-left side perspective view of the atmospheric water generator floor unit showing our design; FIG. 2 illustrates a back-right side perspective view thereof; FIG. 3 illustrates a front view thereof; FIG. 4 illustrates a rear view thereof; FIG. 5 illustrates a right side view thereof; FIG. 6 illustrates a left side view thereof; FIG. 7 illustrates a top view thereof; and, FIG. 8 illustrates a bottom view thereof. The broken lines show portions of the atmospheric water generator that form no part of the claimed design.
